UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

TRAVELING BUCKET EXCAVATOR.

1,289,108.

Specification of Letters Patent. Patented Dec. 31, 1918.

Application filed March 1, 1918. Serial No. 751,414.

To all whom it may concern:

Be it known that I, MORTON G. BUNNELL, a citizen of the United States of America, and resident of Chicago, Cook county, Illinois, have invented a certain new and useful Improvement in Traveling Bucket Excavators, of which the following is a specification.

My invention relates to excavators in general, but more particularly to those for use in constructing ditches for drainage purposes, and especially those in which the excavating apparatus comprises a runway extending transversely of the ditch, together with an endless series of buckets traveling on said runway, from one side of the ditch to the other, whereby the dirt is taken from one sloping bank of the ditch and carried across and up the other bank and discharged at one side thereof.

Generally stated, the object of my invention is to provide an improved and highly efficient excavator of the foregoing general character.

A special object is to provide an excavator of that kind in which an endless series of buckets is arranged to travel transversely of the ditch, and in which means are provided for enabling the excavator to move ahead while the buckets are at the bottom of the ditch, thereby rendering it unnecessary to repeatedly raise and lower the runway upon which the buckets travel, the excavating apparatus being capable of a progressive cutting away of the dirt in a horizontal direction, by the forward movement of the body upon which the apparatus is mounted, as well as a downward progressive excavating action, and whereby a ditch with sloping banks is produced by simply lowering the excavating apparatus until the maximum depth of the ditch is reached, and by then moving the machine forward while the transversely arranged runway and buckets traveling thereon are down in the ground.

Another object is to provide an improved construction and arrangement whereby, in an excavator of this particular character, each bucket is provided with a movable wall for expelling the load, and with operating means adapted to engage a stop on the runway, when it is desired to dump the load, of such character that as soon as the load is dumped, the bucket will pass under the said stop, whereby it is possible to arrange a

series of buckets of this character for a traveling motion in one direction only, as distinguished from the buckets heretofore employed for this purpose, and which do not continue moving forward after reaching the dumping position, but to the contrary reverse their movement and move backward in the opposite direction.

Another object is to provide an improved construction and arrangement whereby, in the use of a machine of this general character, the ground ahead of the excavator may be prepared and reduced to a level road-bed for the machine to travel over, thus making it possible for the excavator to be employed in digging a ditch on the side of a hill.

It is also an object to provide certain details and features of improvement and combinations tending to increase the general efficiency and serviceability of an excavator of this particular character.

In the accompanying drawings:

Figure 1 is a side elevation of an excavator bucket embodying the principles of my invention.

Fig. 2 is a plan of the bucket and adjacent parts of the sprocket chains shown in Fig. 1.

Figs. 3 and 4 illustrate different sizes of the cutters which are combined with the buckets in an excavator embodying the principles of my invention.

Fig. 5 is a side elevation, of a more or less diagrammatic character, of a side hill excavator embodying the principles of my invention.

Fig. 6 is a detail showing a modification of the construction shown in Fig. 1.

Fig. 7 is a rear elevation of the machine shown in Fig. 5.

As thus illustrated, and referring more particularly to Figs. 1 to 4, inclusive, an excavator constructed in accordance with my invention, comprises a pair of endless sprocket chains *a*, which are spaced apart to accommodate the buckets *B* between them. As the said buckets are all alike, a description of one will be sufficient for all. As shown, the bucket *B* has a lower cutting edge *100* or lip *b* extending across the bottom of the mouth of the bucket, the general shape of the bucket being rectangular. The bucket is made rigid with the links *a*, in any suitable manner, and is provided at its rear end with *110*

a movable wall b^1 , said wall being adapted to slide forward to expel the load from the mouth of the bucket. For this purpose the top of the bucket is provided with parallel 5 guide-ways b^2 between which the slide or traveler b^3 is adapted to move back and forth longitudinally of the bucket, the said slide or traveler being provided with wheels b^4 that travel in the said guide-ways. A 10 sheave b^5 is suitably mounted at the front of the bucket, and a steel cable or other flexible connection b^6 extends around the sheave and connects the movable end wall b^1 with the said slide or traveler b^3 , whereby backward 15 movement of the said slide or traveler, in the manner indicated in dotted lines in Fig. 1, serves to pull the said end wall forward, thus expelling the load. The heel of the bucket is provided with a couple of laterally 20 extending cutters b^7 which extend outside of the sprocket chains, and also outside of the runway C (see Figs. 5 and 7) in which the rollers a^1 of the sprocket chains travel. Thus, and in the downward movement of the 25 endless series of buckets, an excavation is made which is wider than the runway. At a suitable point in the path of travel of the buckets, as at the left in Fig. 7, the runway is provided with a cross bar c , (Fig. 1) or 30 other suitable stop, against which the up-standing portions of the slides or travelers b^3 strike as each bucket passes below and arrives at the point of discharge. When 35 this happens the slide or traveler b^3 stands still, of course, and the result is that the movable end wall b^1 is caused to travel faster than the bucket, thus expelling the load. The rear ends of the tracks or guide-ways b^2 are provided with downwardly 40 curved portions b^8 , said portions overhanging the rear end of the bucket, whereby the slide or traveler b^3 may tilt backward when the rear wheels thereof are disengaged from the rear ends of the guide ways, as shown 45 in dotted lines in Fig. 1, thus permitting the slide or traveler to pass under the cross bar c , this action occurring at about the time that the movable end wall of the bucket reaches the mouth thereof. In this 50 way each bucket automatically discharges its load when it reaches the dumping position, and the movable end walls of the buckets are restored to normal position by the pressure of the dirt at the mouth of the buckets, as each bucket again strikes the 55 ground at the other side of the ditch. To permit the endless series of buckets thus provided to sink gradually into the ground, the runway C is supported for up and down 60 movement on the body frame D of the excavator.

One of the important features of my invention is the ability of the machine to travel slowly forward after the excavating buckets have arrived at the maximum depth

of the ditch. Prior to my invention, it was common for machines of this general class to operate downwardly until the buckets reached the bottom of the ditch, but it was then necessary, however, to raise the runway and buckets out of the ground, move the machine forward the width of the runway, and then allow the excavating apparatus to again sink into the ground. In other words, the ditch was formed by a series of distinct excavating operations, each excavating operation consisting merely of the downward movement of the excavating buckets while the machine was standing still. With my improved construction, however, the buckets and runway move downward until the desired depth is reached, and then the machine starts forward slowly, the buckets working steadily all the time, and with the result that the ditch is formed by a progressive cutting away of the dirt at the end of the ditch, this dirt falling down from the vertical surface from which it is cut, and being gathered up by the buckets at the bottom of the ditch. For this purpose, the said runway C is preferably arranged at the rear end of the machine, as shown more clearly in Fig. 5, and the buckets are provided at their forward sides—that is to say, at the sides of the buckets which face in the direction in which the machine travels, with auxiliary cutters E which are each fastened to one of the cutters b^7 , and which extend upwardly outside of the runway, in advance thereof, and in the direction in which the apparatus is moved bodily to produce the desired excavating operation. These cutters E, it will be seen, are desirably of a length to extend upwardly to the top of the ditch, or nearly so, whereby each cutter scrapes or shaves the entire forward end surface of the ditch in passing downward and across, and then up the other side of the ditch. The dirt thus scraped or shaved from the end of the ditch falls downward, and is gathered up by the buckets at the bottom of the ditch. The height or length of these auxiliary cutters E depends upon the depth desired for the ditch, it being understood, in some cases, that the maximum depth of the ditch will not be greater than the height of the bucket, whereas in other cases, as shown in Fig. 7, the depth of the ditch will be considerably greater. For this purpose a number of sets of cutters E can be provided, some long, and some short, and by making them easily removable, they can be put on and taken off at will. With this arrangement, it will be seen, the runway and series of buckets traveling thereon can be allowed to sink gradually into the ground, while starting the ditch, and when the maximum depth is reached the machine can be slowly started forward, it being understood that the so-called caterpillars F, or other

suitable traction devices, can be employed for supporting the body of the machine upon the ground in advance of the forward end of the ditch. When the machine starts forward, the cutters E work on the face or vertical end surface of the ditch, and the dirt that falls downward is picked up by the buckets at the bottom of the ditch. With this construction, therefore, it is not necessary to repeatedly raise and lower the runway and buckets, as the forward progressive action is accomplished while the buckets and runway are down in the ground.

As shown in Fig. 6, the auxiliary cutters G, similar to those already described, are mounted on the sprocket chains, instead of on the rear ends of the buckets. In such case, the cutters G work above the runway, while the fixed cutters or heel pieces b⁷ of the buckets are relied on to do the necessary cutting below the runway, but the result is otherwise substantially the same as that previously described. In practice, and for the average kind of work, the buckets are arranged about five feet apart, and this insures having at least two buckets always in the ditch. In such case, the spaces between the buckets can be supplied with as many of the cutters G as may be found necessary or desirable.

As shown in Figs. 5 and 7, my invention takes the form of an excavator adapted more particularly for use in constructing a ditch on the side of a hill. For this purpose the front end of the machine is provided with a runway H having an endless series of buckets similar to those already described. The runway C, at the rear end of the machine, is symmetrical in outline, being adapted to determine the cross sectional contour of the ditch, and being provided with sprockets c¹ around which the sprocket chains and buckets travel. The runway H, however, is irregular in outline, having a straight lower portion h that holds the buckets to a straight line of travel, across the front of the machine, and with portions h¹ and h² that converge upwardly and to one side where they come together at a considerable distance uphill from the excavator body. At this point the runway H is provided with sprockets h³, similar to those of the other runway, around which the sprocket chains and buckets travel. This runway H, like the other runway, is mounted for bodily up and down movement, and the buckets of both runways are arranged to discharge on to the downhill side of the ditch, thus forming a spoil bank at this side of sufficient height to make a ditch of the required depth. The runway H is lowered until the portion h holds the buckets at the required depth, forming a flat surface or roadway over which the machine may travel as it moves forward, as shown

more clearly in Fig. 5. In this way the machine builds a level roadway ahead of itself, even when used on a side hill, and then constructs a ditch in the rear thereof.

It will be understood, of course, that in Fig. 7 only a few of the buckets are shown, for convenience of illustration, and that the buckets on the two runways are exactly alike, and are arranged at regular intervals on the sprocket chains thereof. It will also be understood that the construction may be changed in various ways, without departing from the spirit of my invention, and that I do not, therefore, limit myself to the exact construction shown and described.

The two runways C and H can be of any suitable, known or approved construction, and be raised and lowered by any suitable or desired mechanism. With the construction shown in Fig. 1, the runways can be of channel iron with the channels turned inward; but with the construction shown in Fig. 6 it is possible that angle irons will be more suitable for the said runways, although it is obvious that the construction of said runways can be of any character which will not interfere with the proper working of the auxiliary cutters E and G—that is to say, which will permit these cutters to travel around in such manner as to cut the dirt from the end wall of the ditch. As shown in Fig. 7, the auxiliary cutters E reach nearly to the ground line—that is to say, are nearly high enough to reach to the ground level upon which the machine travels. This enables the said cutters to carry away enough dirt to cause what little dirt remains above to cave in and tumble down to the bottom of the ditch. Obviously, however, the length of the auxiliary cutters and the proportions of the other parts of the machine, can be so regulated or adjusted that the upper end of each cutter will extend to the ground level upon which this machine travels, or even above, if such is necessary. In practice, however, and as shown, it will be sufficient if these cutters are large enough to cut the dirt away a substantial distance above the tops of the bucket, whereby the dirt remaining at the top will readily break away and fall to the bottom of the ditch.

I do not limit myself to the exact construction shown and described.

The particular construction of excavating bucket herein shown and described is claimed in my divisional application Serial No. 847,801, filed June 29, 1914.

What I claim as my invention is:

1. An excavator for making a ditch on a side hill, comprising a body mounted to travel ahead of the excavation, and means on the rear end of said body to make a ditch as the excavator moves slowly forward, so that a ditch of full depth is made by one

continuous forward operation of the excavator, said means including an endless series of digging buckets arranged to travel from the upper side of the ditch to the lower side, 5 a runway for said buckets, and cutters arranged to operate in front of said runway, said body having its forward end provided with means operating continuously during the forward motion of said body to form 10 a level road for the excavator, and to form a slope for the inner side of the ditch.

2. An excavator for making a ditch on a side hill, comprising a traveling body, a transversely-arranged digging apparatus at 15 the front end of said body to level the

ground and extending outward and upward at one side of the excavator to operate on a hill-side, and to form a slope for the inner side of the ditch, and a transversely-arranged digging apparatus on the rear end 20 of said body for cutting a ditch with sloping sides and to form a spoil bank at the lower side thereof.

Signed by me at Chicago, Illinois, this 26th day of February, 1913.

MORTON G. BUNNELL.
